UNITED STATES PATENT OFFICE

JOSEPH W. BETTENDORF, OF BETTENDORF, IOWA

CAR-TRUCK SIDE FRAME

Application filed February 23, 1928. Serial No. 256,200.

This invention relates to car truck side frames and more particularly to an advantageous form of integral cast steel side frame.

Objects of the invention are to provide an integral cast steel side frame of substantially non-porous metal, of improved metallurgical structure, of smooth surfaces as cast, and of generally improved characteristics.

Other objects of the invention will be apparent to those skilled in the art from the disclosure herein made.

Heretofore railroad car truck side frames of the integral type have been sand cast. The resulting cast metal has been porous in nature, and metallographically has been that ordinarily known as Widmanstättian structure. As is well known, steel in this condition does not possess its best properties, and an annealing or other heat treating operation is usually necessary before the side frame is used in the car truck. Moreover, the surface of the resulting castings has ordinarily been quite rough and impregnated with particles of burned sand. Fins, surface blow holes, and other surface irregularities have also occurred as the result of forming the side frames by sand casting. To prepare such castings for use in railroad cars, it has been usually found necessary to chip off surface irregularities and to sand blast or chip the exterior surfaces of the side frame. Furthermore, it has been necessary to chip or otherwise mechanically prepare those portions of the side frame which must be of relatively accurate dimensions and relatively smooth, such as, for example, the seats for springs, bolsters, and bearings. Such treatment and surface finishing has been relatively expensive and has necessarily decreased the rate of production and increased the cost of the side frames.

By my invention I have provided a cast steel integral side frame of solid, non-porous, homogeneous metal, said metal having generally advantageous metallurgical characteristics. My improved side frame further has smooth exterior surface as cast, whereby substantially no surface finishing is required.

50 A form of side frame to which my inven-

tion is applicable is shown in the accompanying drawings, wherein:

Figure 1 is a top plan view of the side frame;

Fig. 2 is a front elevation of the side frame 55 shown in Fig. 1;

Fig. 3 is a vertical section taken on line 3-3 of Fig. 2; and

Fig. 4 is a vertical section taken on line 4-4 of Fig. 4. 60

The side frame illustrated is shown as comprising longitudinally extending top and bottom members or chords 1 and 2 respectively, and two substantially vertical columns or struts 3 extending between members 1 and 2. The top member 1 is connected to the bottom member 2 adjacent the ends of the frame. Struts 3 divide the space between members 1 and 2 into three apertures, the central one of which is roughly quadrilateral and the other two of which are roughly triangular. The members 1 and 2 are shown as U-shaped in cross section, the central web of the top member being on top and the bottom member being on the bottom. The struts 3 are integral with members 1 and 2 and are also U-shaped in cross section, the central webs of these struts being on the sides toward the central aperture. The portions 4 of the webs of the struts 3 form bolster guides. The portion of the member 2 intermediate the struts 3 has an upper plate 5 forming a spring seat, said spring seat having an aperture 6 substantially centrally thereof. At the end of the side frame adjacent the junctions of the members 1 and 2 are integrally formed the journal boxes 7. The top member 1 is shown as extending over the journal boxes 7, the ends of the member 1 being shown as open. Brake hanger brackets 8 are shown as formed 90 integrally with the top member 1. 85

A side frame having the advantageous features of my invention previously mentioned may be obtained by casting said side frame with the outer surfaces thereof against metal parts. This is preferably accomplished in a metal permanent mold. The bearing surfaces of the side frame, such as the surfaces 4 and 5, are preferably cast against metal mold parts. The interior surfaces of the side 100

frame, such as the interior surfaces of the journal boxes and the interior surfaces of the U-shaped members may be formed against sand or metal, as desired.

5 I have found that by casting a side frame in a permanent mold the grain structure and general metallurgical characteristics of the side frame metal are greatly improved whereby annealing or other heat treatment of the
10 side frame generally is ordinarily made unnecessary with the obvious economic advantages.

15 I have further found that the metal of side frames cast in permanent molds is substantially non-porous, whereby the strength thereof is greatly increased over the porous structure which, as is well known, obtains in the sand cast side frames.

20 I have furthermore found that side frames cast in permanent molds have exterior surfaces which are smooth and uniform and which require generally no chipping or sand blasting to prepare said castings for use in car trucks.

25 It will thus be seen that I have provided a new and novel side frame of the integral cast steel type having advantageous characteristics not heretofore obtained.

30 It will further be noted that I have provided a new and novel car truck side frame having smooth surface characteristics as cast, such that further surface cleanings and preparation is substantially eliminated.

35 It will also be noted that I have provided a new and novel integral cast steel side frame of improved metallurgical characteristics whereby a stronger article is formed not requiring heat treatment subsequent to casting.

40 Furthermore, it is to be understood that the particular forms of apparatus shown and described, and the particular procedure set forth, are presented for purposes of explanation and illustration and that various modifications of said apparatus and procedure can
45 be made without departing from my invention as defined in the appended claim.

What I claim is:

46 The hereindescribed cast car truck side frame member having integral bolster guides and an integral spring seat, the external surfaces of said frame member as cast being of smooth, fine grained, homogeneous surface structure free from surface imperfections, and said bolster guides and spring seat as cast being fine grained, strong and relatively hard, thereby providing efficient bearing surfaces.

51 In testimony whereof I affix my signature.
JOSEPH W. BETTENDORF.
